FELLING MACHINE FOR JOINING FABRIC SECTIONS

Charles S. Thompson, Elmhurst, Ill., assignor to
Union Special Machine Company, Chicago, Ill.,
a corporation of Illinois

Application July 12, 1933, Serial No. 680,127

11 Claims. (Cl. 112—151)

The invention relates to new and useful improvements in a felling machine for joining fabric sections, and more particularly to the construction of the presser foot used therein. In my applications Serial Nos. 633,898 and 633,899, filed September 19, 1932, there is shown, described and claimed a felling machine wherein the fabric sections are gripped at each side of the interfolded parts of the seam for the feeding of the fabric sections.

An object of the present invention is to provide a machine of the above type with a presser foot having means cooperating with the foot to grip the fabric sections at each side of the interfolded portions, and a section located directly above the interfolded portions for controlling the feed of the same, and in particular during the passing of cross seams, which section may be locked in a set position or may yield, and may be placed either so that it is normally in contact with the interfolded fabric sections or spaced above the same.

A further object of the invention is to provide a felling machine with a presser foot having fabric engaging sections arranged in tandem wherein said sections are pivotally mounted on a supporting yoke which in turn is pivotally mounted on the presser bar, and wherein there is means carried by the presser bar for preventing undue swinging of the yoke when the foot sections are raised for the insertion or removal of the material.

A still further object of the invention is to provide a felling machine of the above type wherein the front section of the presser foot is pivotally supported on a supporting yoke and yieldingly held in a substantially horizontal position.

In the drawings—

Figure 1 is a view of a portion of a machine showing my improvements applied thereto;

Fig. 2 is a sectional view on the line 2—2 of Fig. 1;

Fig. 3 is a sectional view on the line 3—3 of Fig. 2;

Fig. 4 is a bottom plan view of the presser foot;

Fig. 5 is a vertical sectional view in the line of feed; and

Fig. 6 is a transverse sectional view showing a modified form of arrangement of the portions of the foot engaging the fabric sections at the opposite sides of the interfolded portions.

The invention is directed to a machine for joining the edges of fabric sections by a felled seam. It includes a folder for overfolding the edge portion of one fabric section and for under-

folding the edge portion of the other fabric section, and the interengaging of the folded portions. The stitching mechanism, as illustrated, includes three needles, and preferably there is a looper which cooperates with each needle, so as to form independent lines of stitching. The material is fed across the work support by a feeding mechanism including a four-motion feed dog. The material is held on the work support by a presser foot which includes two fabric engaging sections operating in tandem. The feed dog has feeding sections cooperating with each of the fabric engaging sections on the presser foot. The presser foot, the throat plate, and the feeding sections are so constructed as to grip the fabric sections independently at opposite sides of the interfolded portions of the fabric sections for the feeding of the same. Each section of the presser foot has a channel therethrough to receive and guide the interfolded portions of the fabric sections. There are sections of the feed dog engaging the interfolded portions of the fabric sections on the under face thereof. The rear section of the presser foot is provided with a shiftable section which is located in the channel, receiving and directing the interfolded portions of the fabric sections. This member may be yieldingly pressed toward the fabric sections and an adjustable stop is provided for limiting its downward movement, so that said yielding section may be caused to engage, if desired, the interfolded sections, or be slightly spaced above the same and only operated when a cross seam passes to engage and aid in the feeding of the fabric sections during the passing of such cross seam. It may also be locked in a set position.

It is thought the invention will be better understood by a detail description of the illustrated embodiment thereof. In the drawings, the sewing machine is shown as including a supporting base 1 which extends upwardly in the form of a standard 2. A needle head 3 is carried by an overhanging portion mounted on the standard, and the work supporting arm 4 is suspended from the standard. The machine, as shown, is of the type illustrated in the patent granted Norman V. Christensen et al., December 24, 1929, #1,741,095, and further description of the machine is not thought necessary.

Mounted on the work supporting arm is a folder 5 which is of the usual type and consists of two cooperating sections, one of which overfolds the under fabric section and the other of which underfolds the upper fabric section. These folded portions are directed so that they are inter-

114. *Uridiplosis* is a genus of dipterous insects in the family Ulidiidae. The species are predaceous on aphids and other soft-bodied insects.

spective fabric sections for the feeding of the same. Beneath this shiftable portion 35 is the section 44 of the feed dog, and when said portion 35 contacts with the interfolded fabric sections by a cross seam passing through the machine, then the feed dog section 44 will aid in the feeding of the interfolded stitched together portions of the fabric sections.

In Fig. 6 of the drawings there is shown a slightly modified form of presser foot, throat plate and feed dog, wherein the portion 43 of the presser foot is on the same level as the portion 42. The throat plate is of the same height at opposite sides of the interfolded portions of the fabric, and the feed dog is correspondingly shaped so that the fabric sections at each side of the interfolded portions thereof will be gripped for the principal feeding of the fabric sections. The shiftable portion 35 is of the same construction as that described above, and operates in the same manner. In this figure of the drawings, this shiftable portion is shown in a set position spaced above the fabric sections under normal interfolding conditions.

The yoke 18 is capable of a limited movement on its pivotal connection 20. Directly above the yoke are shoulders 45 which are spaced slightly above said yoke, and said shoulder is out of contact with the yoke when the two foot sections are pressed into contact with the smooth surface of the throat plate, or into contact with fabric sections of uniform thickness. When a fabric section is led beneath the front portion of the foot, it can be bodily raised, and the yoke will swing on the rear section of the foot to permit this easy passing of the fabric sections beneath the foot. The pivotal connection permits this swinging of the yoke while the presser bar moves in a vertical direction. The same is true when the fabric is passing from beneath the rear section of the foot. It will be elevated, although the front section moves down on to the throat plate, and will properly hold and control the fabric sections until they are fed from beneath the foot. The yoke will also permit the foot sections to raise and lower to accommodate cross seams as they pass first beneath one and then the other of the foot sections. These shoulders will prevent abnormal swinging of the yoke when the foot sections are raised clear of the work support for the insertion or removal of material. The shoulders limit the swinging movement and maintain the foot sections substantially on the same level.

It is obvious that minor changes in the details of construction may be made without departing from the spirit of the invention as set forth in the appended claims.

Having thus described the invention, what I claim as new and desire to secure by Letters Patent, is—

1. In a felling machine, the combination of a work support, a feeding device and a presser foot, said presser foot including a front section, a rear section, a pivoted yoke to which said sections are independently pivoted, each section of the presser foot having a channel in its under face for receiving and directing the interfolded portions of the fabric sections, said rear section of the presser foot having a shiftable portion in said channel directly above the interfolded portions of the fabric sections.

2. In a felling machine, the combination of a work support, a feeding device and a presser foot, said presser foot including a front section, a rear

section, a pivoted yoke to which said sections are independently pivoted, each section of the presser foot having a channel in its under face for receiving and directing the interfolded portions of the fabric sections, said rear section of the presser foot having a shiftable portion in said channel, a supporting stem to which said shiftable portion is fixed, means for supporting said stem on said rear section of the foot so that it moves in a direction at right angles to the fabric engaging section of said foot, a spring bearing on the stem for yieldingly pressing said portion downwardly, and an adjustable stop for limiting the downward movement of said shiftable portion.

3. In a felling machine, the combination of a work support, a feeding device and a presser foot, said presser foot including a front section, a rear section, a pivoted yoke to which said sections are independently pivoted, each section of the presser foot having a channel in its under face for receiving and directing the interfolded portions of the fabric sections, said rear section of the presser foot having a yielding portion in said channel, a supporting stem to which said yielding portion is fixed, means for supporting said stem on said rear section of the foot so that it moves in a direction at right angles to the fabric engaging section of said foot, a collar having a threaded connection to said stem and serving as a stop for limiting the downward movement of said yielding portion, and a spring bearing on said collar for forcing the stem downward.

4. In a felling machine, the combination of a work support, a feeding device and a presser foot, said presser foot including a front section, a rear section, a pivoted yoke to which said sections are independently pivoted, each section of the presser foot having a channel in its under face for receiving and directing the interfolded portions of the fabric sections, said rear section of the presser foot having a yielding portion in said channel, a supporting stem to which said yielding portion is fixed, means for supporting said stem on said rear section of the foot so that it moves in a direction at right angles to the fabric engaging section of said foot, a collar having a threaded connection to said stem and serving as a stop for limiting the downward movement of said yielding portion, and a spring bearing on said collar for forcing the stem downward, said collar having grooves formed therein adapted to house the spring for preventing the turning of the collar on the stem when said spring is in engagement therewith.

5. In a felling machine, the combination of a work support, a feeding device, a presser foot, a presser bar, said presser foot including a front section and a rear section arranged in tandem, a yoke to which said sections are independently pivoted, means for pivotally connecting said yoke to said presser bar, a spring carried by said yoke and bearing on the front section of the presser foot for yieldingly holding said front section in a predetermined set position, and a spring carried by said yoke and bearing on the rear section of the presser foot for normally holding the front end thereof yieldingly depressed.

6. In a felling machine, the combination of a work support, a feeding device, a presser foot, a presser bar, said presser foot including a front section and a rear section arranged in tandem, a yoke to which said sections are independently pivoted, means for pivotally connecting said yoke to said presser bar, shoulders carried by said presser bar above said yoke and limiting the turning

movement of the yoke on its pivotal connection, and a spring carried by said yoke and bearing on the front section of said presser foot for yieldingly holding said front section in a predetermined set position on said yoke.

7. In a felling machine, the combination of a work support, a feeding device, a presser foot, a presser bar, said presser foot including a front section and a rear section arranged in tandem, a yoke to which said sections are independently pivoted, means for pivotally connecting said yoke to said presser bar, shoulders carried by said presser bar above said yoke and limiting the turning movement of the yoke on its pivotal connection, a spring carried by said yoke and bearing on the front section of said presser foot for yieldingly holding said front section in a predetermined set position on said yoke, and a spring carried by said yoke and bearing on the rear section of the presser foot for normally holding the front end thereof yieldingly depressed.

8. In a felling machine, the combination of a work support, a feeding device, a presser foot, a presser bar, said presser foot including a front section and a rear section arranged in tandem, a yoke to which said sections are independently pivoted, means for pivotally connecting said yoke to said presser bar, and shoulders carried by said presser bar above said yoke and limiting the turning movement of the yoke on its pivotal connection, each of said presser foot sections having a channel in its under face for receiving and directing the interfolded portions of fabric sections, said rear section of the presser foot having a yielding portion in said channel directly above the interfolded portions of the fabric sections.

9. In a felling machine, the combination of a work support, a feeding device, a presser foot, a presser bar, said presser foot including a front section and a rear section arranged in tandem, a yoke to which said sections are independently pivoted, means for pivotally connecting said yoke to said presser bar, and shoulders carried by said presser bar above said yoke and limiting the turning movement of the yoke on its pivotal connection, each section of the presser foot having a channel in its under face for receiving and directing the interfolded portion of the fabric sections, said rear section of the presser foot having a yielding portion in said channel directly above the interfolded portions of the fabric sections, a stem attached to said yielding portion, means for guiding said stem on said presser

foot section in a direction at right angles to the fabric engaging face of the foot section, a collar threaded above said stem and limiting the downward movement thereof, and a spring carried by said rear foot section and bearing on said collar for forcing the stem downward.

10. In a felling machine, the combination of a work support, a feeding device, a presser foot, a presser bar, said presser foot including a front section and a rear section arranged in tandem, a yoke to which said sections are independently pivoted, means for pivotally connecting said yoke to said presser bar, shoulders carried by said presser bar above said yoke and limiting the turning movement of the yoke on its pivotal connection, each section of the presser foot having a channel in its under face for receiving and directing the interfolded portion of the fabric sections, said rear section of the presser foot having a yielding portion in said channel directly above the interfolded portions of the fabric sections, a stem attached to said yielding portion, means for guiding said stem on said presser foot section in a direction at right angles to the fabric engaging face of the foot section, a collar threaded above said stem and limiting the downward movement thereof, and a spring carried by said rear foot section and bearing on said collar for forcing the stem downward, said collar having grooves formed therein for receiving and housing the spring, whereby when said spring is in engagement with the collar, said spring will hold said collar from rotating on said stem.

11. In a felling machine, the combination of a work support, a feeding device and a presser foot, said presser foot including a front section, a rear section, a pivoted yoke to which said sections are independently pivoted, each section of the presser foot having a channel in its under face for receiving and directing the interfolded portions of the fabric sections, said rear section of the presser foot having a shiftable portion in said channel, a supporting stem to which said shiftable portion is fixed, means for supporting said stem on said rear section of the foot so that it moves in a direction at right angles to the fabric engaging section of said foot, a spring bearing on the stem for yieldingly pressing said portion downwardly, an adjustable stop for limiting the downward movement of said shiftable portion, and means whereby said shiftable portion may be locked in a set position.

CHARLES S. THOMPSON.
